UNITED STATES PATENT OFFICE.

FREDERICK A. FOXHALL, OF HOMESTEAD, PENNSYLVANIA.

GRIP.

Application filed December 18, 1920. Serial No. 431,678.

To all whom it may concern:

Be it known that I, FREDERICK A. FOXHALL, a citizen of the United States, and resident of Homestead, in the county of Allegheny and State of Pennsylvania, have invented certain new and useful Improvements in Grips, of which the following is a specification.

This invention relates to gripping devices and more particularly to a skull cracker grip adapted to lift a heavy skull cracker ball, a considerable distance in the air, and then to be opened allowing the ball to fall and strike an article to be broken, 15 which is positioned immediately below the ball.

One of the principal objects of the present invention is to provide a lock for holding the jaws of the grip in closed position 20 until unlocked by the operator, thus preventing premature release of the ball with its resultant dangers.

Another object of the invention is to provide a grip having a lock that may be operated by the same cable or chain used to trip the grip, thus facilitating the operation of the device and allowing the operator to be stationed a safe distance from the skull cracker before he releases the lock.

30 A still further object of the invention is to provide a grip of the class described that is strong and durable, and is formed of a minimum number of parts, thereby providing a practical and safe device for the use 35 to which it is intended.

Referring now to the drawings, Figure 1 is a side elevation of my improved grip.

Figure 2 is a top plan thereof.

Figure 3 is a side elevation on a larger scale, of a portion of the apparatus showing details in the construction of the locking members.

Figure 4 is a plan of the parts of the apparatus illustrated in Figure 3.

45 In the accompanying drawings, forming part of this specification, the gripping mechanism has two limbs, 2 and 3, which are pivotally connected intermediate their ends, and have curved or hooked lower ends 4 and 5, and straight shank portions 6 and 7, respectively. The shank portion 6 of the limb 2 has its upper end pivotally connected to a clevis 8 to which the chain hook of the skull cracker crane, or other lifting mechanism is attached when the grip is in use.

The other limb 3 has the upper end of its

shank 7 detachably held, by engagement with the head 9 on the hook end of the tripping lever 10, so as to secure the curved lower ends 4 and 5 of the limbs 2 and 3 in 60 closed position. The lever 10 is pivotally mounted on a bolt 11, which conveniently is used also to secure a clevis 8 to the upper end of the shank 6 of the limb 2.

The curved lower ends 4 and 5 of the 65 limbs 2 and 3 when in closed position are adapted to engage with the eye or link 12 of a skull cracker ball and hold the ball, as will be apparent by reference to the drawings.

70 The safety lock by which the hooked end of the tripping lever 10 is secured in position to maintain the limb 3 of the grip in closed position and prevent tripping thereof accidentally, comprises a cam 13 on a shaft 75 14 which is mounted so as to turn or oscillate in a suitable opening formed in the head 9; and a swinging cam operating lever 15 is secured to the upper end of the shaft 14 and is arranged to turn or oscillate the 80 shaft so as to move the cam into and out of locking engagement with the upper end of the shank 7 of the limb 2.

85 The cam 13 is positioned within a slot in the shank engaging face of the head 9, and is arranged to turn or oscillate through part of a revolution so as to enter and move out of the slot or keeper 16 in one face of the beveled upper end of the shank 7 of the limb 3.

90 The outer end of the swinging cam lever 15 is connected to one end of a tripping chain or cable 18 which extends rearwardly through an opening or hole 19 in the rear end of the tripping lever 10 and then downwardly to the ground where it may be grasped by an operator. The chain or cable forming the flexible connection 18 is provided with a large link or stop 20 to limit its free movement through the opening 19, 100 thereby limiting its action on the cam lever 15 and, after moving the cam lever 15 so as to move the cam out of the slot 16, cause the pull of the chain 18 to be exerted on the tripping lever 10 to lift the head 9 and 105 thereby trip the limbs of the grip and release the skull cracker ball 12.

110 The cam lever 15 is yieldingly held in locked position by the spring pressed pin or latch 25 mounted in the upper face of the head 9 of the tripping lever 10, this pin being arranged to fit within a recess or hole

26 in the under side of the lever 15. The pin 25 prevents the lever 15 from accidentally turning to release the cam 13 since it requires a jerk of considerable force to cause the lever to ride over the upper end of the pin 25.

5 The operation of the device is as follows:—

10 The limbs 2 and 3 of the grip will be closed around the eye or link 12 of the skull cracker ball so that when the grip is lifted it will raise the ball. The tripping lever 10 will then be moved by hand to engage the upper end of the shank 7 of the limb 3, 15 and the cam lever 15 will be turned to move the cam 13 into the slot or keeper 16 in the end of the shank 7, thereby locking the tripping lever 10 in engagement with the limb 3, these adjustments being made while 20 the device is in lowered position where the apparatus is within reach of an operator on the ground.

25 After the device is locked, the skull cracker crane will be started so as to lift the grip and attached ball to the proper height from which it is desired to be dropped. The operator then pulls on the lower end of the chain or cable 18, giving it a sharp jerk. This jerking movement 30 of the member 18 first moves the cam lever 15 so as to release the cam 13 from the slot or keeper 16 in the upper end of limb 3.

35 When the cam has moved into released position, the large link or stop 20 on the member 18 will have moved into engagement with the eye on the end of the tripping lever 10 and will then tilt the lever so as to disengage the head 9 from the upper end of the limb 3 of the grip, and permit the grip to open and allow the ball to fall.

40 It will be readily apparent that the above described grip being safe and incapable of becoming accidentally released while being lifted, forms a great improvement over the art.

45 It will also be apparent that while the grip is described in connection with a skull cracker, it is not limited to such use, but may be used in lifting any articles desired.

50 While I have described one particular embodiment of my invention it is only illustrative, and I do not wish to be limited thereto, since various modifications may be 55 made within the scope of the appended claims, without departing from the spirit of my invention as defined in the appended claims.

I claim:—

60 1. A grip comprising a pair of limbs pivotally connected intermediate their ends, said limbs having curved lower ends forming a hook portion when closed, a tripping lever adapted to engage and hold said limbs

in closed position, means for locking said 65 tripping lever to said limbs, and means for releasing said locking means and tripping said lever.

2. A grip comprising a pair of limbs pivotally connected intermediate their ends, 70 said limbs having curved lower ends forming a hook portion when closed, a tripping lever pivotally mounted on one limb, and having a head forming a hook adapted to engage the other of said limbs to hold the 75 limbs in closed position, means mounted on said head for locking said tripping lever to said second limb, and means for releasing said locking means and tripping said lever.

3. A grip comprising a pair of limbs pivotally connected intermediate their ends, 80 said limbs having curved lower ends forming a hook portion when closed, a tripping lever pivotally mounted on one limb, and having a head on one end adapted to engage the other of said limbs to hold the 85 limbs in closed position, a locking cam mounted on a shaft journaled in said head and adapted to move in a slot in said head into a slot in said second limb, and means 90 for releasing said locking cam and tripping said lever.

4. A grip comprising a pair of limbs pivotally connected intermediate their ends, 95 said limbs having curved lower ends forming a hook portion when closed, a tripping lever pivotally mounted on one limb and having a head on one end adapted to engage the other limb to hold said limbs in closed position, a locking cam mounted on said head and adapted to move through a slot therein into a slot in said second limb, a lever secured to said shaft and adapted to rotate the same to move said cam into and out of 100 said slot in said second limb, and a flexible member adapted to operate said last named lever, and to trip said tripping lever.

5. A grip comprising a pair of limbs pivotally connected intermediate their ends, 110 said limbs having curved lower ends forming a hook portion when closed, a tripping lever pivotally mounted on one limb, and having a head on one end adapted to engage the other limb to hold said limbs in 115 closed position, a locking cam mounted on a shaft journaled on said head and adapted to move in a slot in said head and engage a slot in said second limb, a lever secured to turn the cam shaft, to move said cam into and out of the slot in said second limb, means for yieldingly holding said lever when said cam is in locked position, and a flexible member adapted, when pulled, to operate said cam lever and to trip said tripping lever.

In testimony whereof, I have hereunto signed my name.

FREDERICK A. FOXHALL.
